[57] CLAIM

The ornamental design for a fan for automotive generator, as shown and described.

DESCRIPTION

FIG. 1 is a perspective view of a fan for automotive generator showing my new design;

FIG. 2 is a side elevational view thereof on an enlarged scale;

FIG. 3 is a front elevational view thereof on an enlarged scale;

FIG. 4 is a rear elevational view thereof on an enlarged scale;

FIG. 5 is a fragmentary front elevational view of a second embodiment of my design on an enlarged scale, the remainder of the fan being omitted for convenience of illustration, it being understood that the second embodiment differs from the first only in the configuration of the center aperture.

FIG. 1

FIG. 2

FIG. 3

FIG. 5

FIG. 4
